DES. 2168

Francis J. Pierce of Roxbury, Mass.

Assignor to

Roxbury Carpet Company of same place

Letters Patent No 2168. Dated Sept. 12, 1875

Design for a Carpet Pattern

The Schedule referred in these Letters Patent and making part of the same.

To all Persons to whom these Presents shall come,

Be it known that I Francis J. Pierce of Roxbury, in the County of Norfolk and State of Massachusetts have invented or produced an ornamental Design for a Carpet, or other fabric or manufacture and do hereby declare the same to be fully represented in the accompanying drawing.

A lozenge-shaped tablet or shield, a, ornamented with scrolls of leaves on its corners, encompasses a bunch of flowers, b, and is surrounded by four quarterings, c, d, c', d', arranged against its four sides.

The two quarterings, c, c' or d, d', directly against each two opposite sides of the tablet contain two separate portions of a representation of a bouquet of flowers arranged within a border. The scroll leaves are continued from the angles of the shield between the next adjacent quarterings and along their outer edges, the whole being as exhibited in the said drawing.

I claim the said design as described and represented.
